UNITED STATES PATENT OFFICE.

CHARLES A. RANDALL, OF NEW YORK, N. Y.

THERMO-ELECTRIC GENERATOR.

SPECIFICATION forming part of Letters Patent No. 244,366, dated July 19, 1881.

Application filed May 11, 1881. (No model.)

To all whom it may concern:

Be it known that I, CHARLES A. RANDALL, a citizen of the United States, residing at New York, in the county of New York and State of New York, have invented new and useful Improvements in Thermo-Electric Generators, of which the following is a specification:

This invention relates to that class of apparatus known as "thermo-electric" batteries or generators, in which the electric current is established by applying heat to one of the junctions in a circuit composed of two different metals. As is well known, extremes of temperature favor the development of the current in these batteries, so that if heat be applied to one junction and cold to the other a more powerful current will be produced than by heating alone.

The essential object of my invention is to utilize the heat generated in a stove, range, or furnace employed for heating or for culinary purposes both for the purpose of heating one part or portion of a thermo-electric element or elements of a thermo-electric generator to a very high degree of temperature, and also for producing the cold to which the opposite part or portion of the element is to be subjected.

My invention consists, first, in a system of thermo-electric generation, the combination of one or more thermo-electric elements with a heating and a freezing apparatus, respectively adapted to subject said elements to a high degree of heat and to a temperature below the freezing-point for the production of electricity, as described; second, in a system of thermo-electric generation, the combination, with a heating apparatus the heat from which is employed for the production of cold, of one or more thermo-electric elements arranged to be subjected to the action of the heat and cold for the production of electricity; third, in a system of thermo-electric generation, one or more thermo-electric elements, in combination with an apparatus for producing ice and a range or furnace; fourth, in a thermo-electric generator, the combination of metals differing in texture or grade, or of metal and carbon, arranged in circuit and subjected to the action of heat, and also to a low degree of temperature by means of a freezing apparatus, substantially as described.

In the accompanying drawings, Figure 1 is a perspective view of a furnace or range adapted for household purposes, said figure also illustrating a portion of an ice-machine, with one electrode or terminus of each element of a thermo-electric battery extended out from the side of the range, and also from the ice-tank. Fig. 2 is a view of one element of a thermo-electric battery composed of different metals; Fig. 3, an edge view of three elements of a different size from Fig. 2; Fig. 4, a like view of two of the same, constructed with intermediate pieces of metal and carbon; Fig. 5, a similar view of one of said plates or elements composed of different metals, or of metal and carbon.

A indicates an ordinary cooking-range, which can be adapted to my invention with but little expense.

B refers to the elements of a thermo-electric battery, each element consisting of a strip, bar, or plate composed of several metals, for purposes well known in the construction of a battery of this character.

In the present instance let C C indicate pieces of copper or other metal suitable for the purpose, connected together by a conductor, B', of different texture—such, for example, as bismuth, antimony, German silver, carbon, or alloys of metal—so as to form a continuous plate, which constitutes one element of a thermo-electric generator. These metals or metals and conductors can be combined in various ways, the object being to provide an element of a thermo-electric battery which can be arranged so that one portion thereof will be subjected to the heat from the fire in a range, furnace, or analogous heating apparatus and the opposite terminus of said element be extended out from the furnace into a suitable freezing-tank or refrigerating apparatus. These plates or parts of the elements, which are arranged in close proximity to the fire, are insulated from each other, and pass through the range, so as to extend out from both sides thereof, one piece C of copper or other suitable material being within the furnace, so that it will be subjected to the action of the heat, and the other piece C of the same element being extended into the ice-tank D of an ice-machine, so that it will be exposed to a low degree of temperature during

the process of refrigeration caused by the ammoniacal gas passing through the pipes *d* in said tank, the said pieces *C C* being connected together substantially as in Figs. 3, 4, or 5, as described. As many of these elements may be employed as may be found desirable.

In the present instance the ammonia-still for the ice-machine is arranged within the range, so that the same fire that is employed for culinary and heating purposes and for heating the oven also serves to heat the still and cause the ammonia therein to boil.

E indicates the condenser of the ice-machine, in which are arranged the pipes *e e*, connected with the still *g* by the pipe *e'*. The pipes in the condenser connect with the pipes in the freezing-tank, as usual, by a pipe, *f*, and the pipe *f'* leads from the freezing or ice tank back to the still. It will be obvious, then, that the elements of the battery that are within the freezing-tank will be subjected to an exceedingly low degree of temperature during the process of making ice.

As ice-machines of this nature are well known, further detailed description of its construction and operation will be unnecessary, no claim being made to the construction thereof, since any suitable refrigerating apparatus could be employed to accomplish the desired result.

The elements of this battery or generator will be connected to form a circuit the same as the elements of a galvanic or mechanical generator. The elements of this battery can be made in various ways without departing from my invention, the main desideratum being the combination of conductors in circuit best adapted to produce the greatest amount of electro-motive force by the application of heat and cold thereto and the application of the same to the greatest range of temperature that can be obtained in the simple, economical, and practical manner hereinbefore set forth. The electric current thus generated can be utilized for various purposes—as, for instance, for household uses, such as electric lighting, electric motors for driving sewing-machines, call-bells, door-bells, burglar-alarms, and other purposes.

In the elements shown in Fig. 4 each element is composed of two pieces, *C*, of copper or other suitable metal, and two intermediate pieces, *A B'*, which may represent a combination of carbon and metal or dissimilar metals, such as bismuth and antimony.

In Fig. 5, *B' C'* also represent said intermediate pieces—one of carbon and the other of

metal; or the said pieces can be of dissimilar metals, as just above stated.

In Figs. 2, 3, 4, and 5, *Y Y* indicate the terminal wire-connections of these elements, the wires connecting with said elements at their extremities uniting at the single wires *Y'*, as shown; or the said terminal wire-connection can be made at or near the inner ends of the plates *C*, as indicated by the wires *W W'*, Figs. 3 and 4.

It will, of course, be understood that the elements of a thermo-electric battery have heretofore been subjected to the action of heat and cold; but prior to my invention the said elements have not been subjected to a degree of heat above 80° Fahrenheit and at the same time to the action of cold at a temperature below the freezing point, or at or below 30° Fahrenheit. By subjecting the elements to such extremes a more powerful current can be obtained than heretofore.

What I claim is—

1. In a system of thermo-electric generation, the combination of one or more thermo-electric elements with a heating and a freezing apparatus adapted to subject said elements to a high degree of heat and to a temperature below the freezing-point for the production of electricity, substantially as described.

2. In a system of thermo-electric generation, the combination, with a heating apparatus the heat from which is employed for the production of cold, of one or more thermo-electric elements arranged to be subjected to the action of the heat and cold for the production of electricity, substantially as described.

3. In a system of thermo-electric generation, one or more thermo-electric elements, in combination with an apparatus for producing ice and a range or furnace, substantially as described.

4. In a thermo-electric generator, the combination of metals of different texture or grade, or of metal and carbon, arranged on circuit and subjected to the action of heat, and also to a low degree of temperature by means of a freezing apparatus, substantially as described.

In testimony whereof I have hereunto set my hand in the presence of two subscribing witnesses.

CHARLES A. RANDALL.

Witnesses:

PHILIP G. RANDALL,
DANFORTH BECKER.
